UNITED STATES PATENT OFFICE.

ARCHIBALD THOMSON, OF PEORIA, ILLINOIS, ASSIGNOR TO FRANK A. HALE, OF PEORIA, ILLINOIS.

WATER CIRCULATOR AND AIR MOISTENER FOR INTERNAL-COMBUSTION ENGINES.

Application filed August 2, 1926. Serial No. 126,668.

This invention pertains to a device for attachment to internal combustion engines. More particularly it pertains to a device to be connected between the radiator of an internal combustion engine and the intake manifold of the latter whereby the vapor created in the radiator may be carried to the combustion chamber of said engine for producing a smoother operation by humidifying the explosive mixture, lessening the carbon deposits, providing a cooler engine and furthermore by a peculiar arrangement of parts provide a forced water circulation through the engine-head and radiator.

In addition to the above advantages, an object of my invention is that while providing for introducing vapor to the combustion chamber a perfect control of the passage through which the vapor passes is made possible through the use of a valve operated in conjunction with the usual throttle-lever so that said passage is more or less constricted according to the position of the said throttle-lever whereby engine action is maintained at its highest efficiency, particularly when used in automobiles. This will be understood from the following description aided by the accompanying drawing wherein:

Figure 1 is a side elevation of an engine and radiator showing my invention as used therewith.

Figure 2 is an elevation of a device as part of my invention, the same adapted to be clamped between the flanges of the engine's carburetor and intake manifold, part of which device is shown in section.

Figure 3 is a plan of the device shown in Figure 2, the same being also in part section taken on line 3—3 of said Figure 2.

Figure 4 is a plan, much reduced in size, of the carburetor and manifold flanges showing the device of Figures 2 and 3 between them and certain lever connections.

Figures 5, 6 and 7 are elevations of a valve viewed from three different positions, and

Figure 8 is a vertical section of a check-valve.

It is well known, of course, that an internal combustion engine operates with greater power and smoothness, is more quiet and flexible, besides being cooler in operation, when moisture is included with the gas charges. It is my purpose herein to make use of the vapors of the radiator as the moisture to be drawn into the engine and at the same time

automatically circulate the cooling water through the water system by the suction impulses of the engine. In addition to this I control the passage through which the vapor is carried to the combustion chamber by means of a valve operated automatically by the throttle-lever when and as the latter is adjusted so that gas charges taken through the carburetor will not be affected by too great an opening of such vapor passage at such times as the engine is placed under greater load and which would reduce the effectiveness of the engine at such times.

In the drawing 1 designates the engine, 2 the radiator, and 3 and 4 the upper and lower water connections, respectively, connecting the two. An air intake tube 5 is connected into the upper water connection 3 and has a nozzle 6 directed toward the radiator substantially as shown, such tube being installed in any suitable part of such connection 3. In this instance it is extended through the usual rubber hose 7 and is suitably clamped thereto in a leak proof manner. The outer upper end of the tube terminates some distance below the top of the radiator and acts as the overflow for such radiator in addition to a further purpose to be made known later. By thus dropping the tube below the top of the radiator a space is maintained in the latter for the accumulation of vapor to be piped to the engine. A conduit 8 extends at one end well above the water line in the radiator and may extend up into the usual cap 9 of the latter. At its other end the conduit opens into one end of a T-coupling 10, there being a check-valve 11, Figure 8, depending from said coupling 10 as shown in Figure 1. The said valve includes a seat 12 against which a ball 13 is designed to seat toward the conduit 8 and is held upon said seat by a light spring 14 resting upon a closure 15 having an escape opening 16. Connected at one end into the T-coupling 10 above the check-valve is a conduit 17 whose other end extends to and has connection into a passage 17' of a member 18 in the form of a plate clamped between the flanges 19 and 20 of the carburetor 21 and intake manifold 22 respectively. Said plate takes the general form of outline of the flanges 19, 20; by preference merely, and has a central opening 23 therethrough in line with the passage (not shown) of both said carburetor and manifold. The plate also has a bore 24 below the open-

ing 23 whose axis parallels the walls of such plate. A valve 25 lies in said bore and is adapted to be oscillated therein, being of the form shown in Figures 5, 6 and 7. That is to say, it is tubular in form but closed at its top and provided with a stem 26 which extends through the opening and out through the top of the plate 18, a forked lever or arm 27, Figure 4, being affixed to its extremity. Said valve has an opening 28 in its wall adapted to register with a passage 29 in the plate 18, Figure 3, such passage opening toward and into the passage 30 of the intake manifold. Part of the lower portion of the valve is cut away so that the described passage 17' may communicate with the valve's bore in any position of such valve, the lower end of the latter bearing upon a closure 31 through a spring 32 surrounding the stem 26, being interposed between the valve and the upper part of the plate 18 within the opening 23. The opening 28 is of a peculiar form. As shown clearly in Figure 5 it has a considerable area as viewed at what may be called its front side, while in Figures 6 and 7, which show opposite sides of the valve, the opening is shown more or less constricted. The opening being large at its middle length narrows into substantially a V-shape at opposite positions all for a purpose to appear later.

In Figure 4 the usual throttle-valve lever 32' is shown connected with which is the operating rod 33. The throttle-lever 32' and the described forked lever 27 are arranged to operate in conjunction and to this end the extremity of the rod 33 may extend between the bifurcations of said arm 27. In said Figure 4 the broken lines indicate the starting position of the throttle for slowest engine speed, while the continuous lines indicate the full opening of the throttle for the highest engine speed. It is my purpose that in these two extremes of position of the throttle the very small or reduced terminals of the opening 28 of the valve 25 shall open toward the passage 29, being the positions shown in Figures 6 and 7, and that when the throttle is about half way open or where the lever 32' and arm 27 are substantially midway of the extreme positions shown, the opening 28 will be practically fully exposed to said passage 29. The said valve is so set therefore within the bore 24 with reference to the throttle opening that these relations are possible, the intent of which is that for instance in starting the area of the passage leading from the radiator through the conduits 8 and 17 will not be so great as to interfere with a proper drawing of air through the carburetor for the desired vapor mixture. However, as the throttle is opened wider for travel on level roads it is the purpose to open wider the intake from the radiator to supply a larger amount of vapor. Again, when added work

is placed on the engine, as in negotiating hills or traveling on "heavy" roads, and the throttle is opened wider it is again the purpose to restrict the flow of vapor from the radiator so that proper volumes of air can pass through the carburetor for the required explosive mixtures.

It is understood that the said valve 25 rotates through a distance equaling that between the extremes of closed and wide open throttle and that at and near the two extremes the narrowed terminals of the opening 28 are brought opposite the passage 29, the opening being so formed otherwise that the amount of opening exposed to the said passage 29 is properly proportioned to the throttle opening and the work to be imposed upon the engine.

Since a considerable space is maintained in the radiator 2 above the water there is always a sufficient quantity of vapor to be drawn upon. And since, also, the tendency of the considerable suction through the conduits 8 and 17 is to tend to create a vacuum within the radiator space and air can only enter the latter through the pipe 5 the air so induced results in a forced water movement from the engine head through the connection 3, the upwardly directed nozzle 6 aiding in this movement and therefore setting up a marked forced water circulation throughout the water system and a consequent better cooling effect on the engine.

The check-valve 11 since opening to the air serves to drain water from the conduit 8 which may collect therein, the water readily leaking past the ball 13 due to the light pressure maintained by the spring 14 and yet the ball will readily close and be held due to suction during engine operation. Again, back pressures from the manifold toward the radiator may escape through said valve.

My arrangement since automatically controlled in the manual operation of the throttle provides against power loss by controlling the vapor intake passage as described in accordance with the requirements for the best engine operation.

I claim—

1. The combination with the carburetor of an internal combustion engine, its throttle-arm, and an intake manifold, of a member interposed between said carburetor and manifold including an opening therethrough connecting the interior of the carburetor and manifold, and also including a bore and an outlet therefrom leading into the manifold, there being a passage in said member communicating with the said bore for the induction of water vapors, said passage being spaced from the said outlet of said bore, a rotatable tubular valve seated in the bore, the cavity of said valve communicating with the said passage, said valve having a port in its wall adapted to register with the outlet, and

an arm to operate the valve, said arm having connection with the throttle arm whereby in the movement of the latter the throttle and said valve are simultaneously operated.

5. 2. The combination with the carburetor of an internal combustion engine, its throttle-arm, and an intake manifold, of a member adapted to be clamped between the carburetor and manifold including an opening connecting the passage of each, and also including a bore and an outlet therefrom leading toward and into the manifold, there being a passage in said member communicating with said bore, a source of water vapor with which said passage is connected, said passage at the bore being spaced from the outlet of said bore, a tubular valve seated in the bore, the cavity of said valve communicating with said passage, said valve having a port in its wall communicating with its cavity and spaced from the passage adapted to register with the opening, and an arm to operate the valve directly connected with the throttle-arm of the carburetor.
25. 3. The combination with a carburetor of an internal combustion engine, its throttle-arm, and an intake manifold, of a member clamped between the carburetor and manifold including an opening therethrough connecting the passages of the two latter, said member having a bore and an outlet leading into the passages of the said carburetor and manifold, a source of water vapor supply, there being a passage in the member connected to said source and with the bore of the member, a rotatable valve having a passage through it adapted to register with both the passage and outlet, said valve adapted

through adjustment thereof to vary the area of the said outlet, and an arm to operate the valve.

4. The combination with a carburetor of an internal combustion engine, its throttle-arm, and an intake manifold, of a member clamped between the carburetor and manifold including an opening therethrough connecting the passages of the two latter, said member having a bore and an outlet leading into the passages of the said carburetor and manifold, a source of water vapor supply, there being a passage in the member connected to said source and with the bore of the member, a rotatable valve having a passage through it adapted to register with both the passage and outlet, said valve adapted through adjustment thereof to vary the area of the said outlet, and an arm to operate the valve operatively connected with the throttle-arm.

5. An article of manufacture comprising a plate to be placed in the intake manifold of an internal combustion engine having an opening extending through it laterally and having a bore whose axis is disposed at an angle to the axis of the bore of the opening, there being an outlet from the bore of said plate opening upon one side of the latter, there also being a passage in said plate leading outside the same and communicating interiorly with the said bore in spaced relation to the said outlet of the latter, and a valve in said bore having a cavity adapted to connect the passage terminating in the said bore of the plate with the said outlet of said bore.

In testimony whereof I affix my signature
ARCHIBALD THOMSON.
